(57) **CLAIM**

I claim, the ornamental design for an laptop table, as shown and described.

DESCRIPTION

FIG. 1 is a top and front perspective view of a laptop table, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a reference perspective view showing how the laptop table can be coupled with a table; and,

FIG. 9 is another reference perspective view showing the laptop table disposed on a table.

The broken lines shown in the figures are for illustrative purposes only and form no part of the claimed design.
